UNITED STATES PATENT OFFICE.

LESTER I. COPE AND ANDREW F. ZINSMASTER, OF PITTSBURGH, PENNSYLVANIA.

BARREL-CLEAT.

1,223,853.

Specification of Letters Patent. Patented Apr. 24, 1917.

Application filed September 14, 1915. Serial No. 50,652.

To all whom it may concern:

Be it known that we, LESTER I. COPE and ANDREW F. ZINSMASTER, citizens of the United States, residing at Pittsburgh, in the county of Allegheny and State of Pennsylvania, have invented certain new and useful Improvements in Barrel-Cleats, of which the following is a specification.

This invention relates to cleats for barrels, and primarily tends to relieve the barrel head from pressure at all times, but especially when the barrel is in an upright position.

Another object of the invention is to provide a binder for holding the barrel staves in engagement with the head of the barrel, in conjunction with reinforcing the barrel head.

A further object is to devise a cleat which is adaptable for use on barrels of various sizes.

Other objects as well as the nature, characteristic features and scope of our invention will be more readily understood from the following description taken in connection with the accompanying drawings and pointed out in the claims forming a part of this specification.

Referring to the drawings:

Figure 1 is a side elevational view of a cleat constructed in accordance with our invention, illustrating the application of the same on a portion of a barrel,

Fig. 2 is a top plan view of a cleat showing the same applied to a barrel, the latter being shown in top plan,

Fig. 3 is a perspective view of the cleat used in this invention, and

Fig. 4 is a modification of the structure shown in Figs. 1 and 2.

In the drawings, in order to illustrate the application of this invention, a barrel 1 is provided, which is shown to be of the usual configuration.

Our improved cleat comprises an oblong metallic strap 3, which has a portion intermediate its ends, and extending along the longitudinal axis thereof, depressed to provide a rib 4, the latter being of a semicircular configuration in cross section and capacitizing as a means for reinforcing the strap and supporting the barrel head to relieve the latter of pressure, when the barrel is turned in an upright position, as shown in Fig. 1. It is to be understood

that the rib 4 is to be made any desired length, but terminating short of the strap ends. The opposite ends of said strap are sufficiently flexible to permit manipulation by hand, whereby said ends may be made adaptable for use on barrels of various configurations and sizes. Each of the ends 5 is provided with an opening 6, through which a securing element, such as a nail is adapted to be passed for engagement with the barrel 1. In Fig. 1 we have shown nails 7 passed through said openings, in order to illustrate the application of the invention. The rib 4 is to be made of sufficient depth to insure contact of the same with the supporting medium, when engaged with the barrel head, so as to positively relieve the latter of pressure when in an upright position.

In use, the inner face of the strap 3 is engaged with the outer face of the barrel head as shown in Fig. 1, and the opposite ends 5 of said strap flexed over the outer terminals of the staves, and into engagement with the outer faces of the latter. The nails are then driven through the openings 6, in order to hold said cleat from displacement. In this position, it will be seen that the rib 4 contacts with the supporting medium, as does also the portions of the ends 5 which are arranged directly over the terminals of the barrel staves.

In the modification shown in Fig. 4, substantially the same construction as that shown in Fig. 1, is disclosed, with the exception that the hoop 2 is engaged with the outer periphery of the barrel, in which instance the opposite ends 5 will engage with the hoop at substantially diametrically opposite points, so that the nails 7 will engage through said opposite ends 5, the hoop 2, barrel staves, and subsequently into the heads of the barrel. This provides a much more rigid structure, in conjunction with the other advantages set forth above for the cleat *per se*.

It will be understood that the above description and accompanying drawings comprehend only the general and preferred embodiment of our invention, and that various minor changes in details of construction, proportion and arrangement of parts may be made within the scope of the appended claims without sacrificing any of the advantages of our invention.

Having thus fully described our invention, what we claim as new and desire to secure by Letters Patent is:

1. A barrel cleat consisting of a metallic strap for snug engagement with a head of the barrel, said strap being stamped along its longitudinal center to provide a rib, the terminals of which fall short of the strap ends, said rib adapted to lie substantially flush with the terminals of the barrel staves for contact with the supporting medium, to relieve the barrel head of pressure when the barrel is in an upright position.
2. A barrel cleat consisting of a metallic strap for engagement with the head of the barrel, the opposite ends of said strap being

inherently flexible to permit engagement of the same over the barrel staves for securement to the latter, and a rib formed on said strap, adapted to lie substantially flush with the portions of the strap, which engage over the barrel staves for contact with the supporting medium, whereby the barrel head is relieved of pressure.

In testimony whereof we affix our signatures in presence of two witnesses.

LESTER I. COPE.
ANDREW F. ZINSMASTER.
